(57) CLAIM

The ornamental design for jar with cap, as shown and described.

DESCRIPTION

FIG. 1 is a bottom perspective view of a jar with a cap in accordance with the present teachings.
 FIG. 2 is a top perspective view of the jar with the cap of FIG. 1.
 FIG. 3 is a front view of the jar with the cap of FIG. 1.
 FIG. 4 is a back view of the jar with the cap of FIG. 1.
 FIG. 5 is a first side view of the jar with the cap of FIG. 1.
 FIG. 6 is a second side view of the jar with the cap of FIG. 1.
 FIG. 7 is a top view of the jar with the cap of FIG. 1; and,

FIG. 8 is a bottom view of the jar with the cap of FIG. 1.
Any portion of the jar with cap between the break in the
sidewall forms no part of the claimed design.
